CONSTRUCTION OF PIERS

Chauncey M. Goodrich, Windsor, Ontario, Canada, assignor to The Canadian Bridge Company Limited, Walkerville, Ontario, Canada

Application January 1, 1945, Serial No. 570,830

7 Claims. (Cl. 61—52)

1

This invention relates to improvements in the fabrication of concrete bridge piers and similar structures.

The primary object of the invention is the provision of a low cost, steel reinforced, concrete bridge pier or similar structure designed to permit erection thereof by an economical method of fabrication which eliminates the necessity of using caissons, air locks and other expensive and hazardous equipment ordinarily employed in the erection of such structures.

A further object is the provision of a steel reinforced concrete bridge pier embodying novel features of design which make it possible to safely effect a substantial reduction in the size or mass of the pier as compared with known types of piers designed to carry the same loads.

A further object is the provision of a steel reinforced concrete bridge pier embodying novel features of design which require considerably less concrete and steel as compared with known types of steel reinforced concrete piers intended for use under the same service conditions.

More particularly, the invention consists in providing a low cost, steel reinforced, concrete bridge pier or similar structure in which a metallic reinforcing and anchoring frame is embedded to strengthen the concrete structure and resist sidewise and over-turning movements thereof, said frame being grounded on bed rock on which the concrete structure is erected and comprising a comparatively small number of tubular members arranged to effectively resist moments tending to overturn the concrete structure or to move it sidewise, said tubular members being anchored in place by relatively short metal dowels extending downwardly through the lower ends thereof into dowel-receiving openings drilled in the bed rock, said dowels being grouted or otherwise secured to the tubular members and to the bed rock.

Another feature consists in providing an improved steel reinforced, concrete bridge pier or similar structure of the character described in which the aforesaid tubular members are inclined so that they are widely spaced at the base of the concrete structure and slope inwardly as they approach the top of said structure. This feature of the invention increases the effectiveness of the tubular members for resisting overturning of the concrete structure and also facilitates the erection of a relatively slender, tapered, concrete bridge pier or similar structure which has a high load bearing capacity.

A further feature of the invention consists in

2

the provision of simple method steps and apparatus whereby piers designed in accordance with my invention may be erected without the use of caissons or air locks.

Other objects, characteristic features and advantages of the invention will be apparent from the following detailed description of the accompanying drawings, in which—

Fig. 1 is an elevational view of a bridge pier fabricated in accordance with my invention.

Fig. 2 is an elevational view showing the bridge pier as it appears when looking in the direction indicated by the arrow X in Fig. 1.

Fig. 3 is a vertical sectional view taken substantially along the section line 3—3 of Fig. 4.

Fig. 4 is a horizontal sectional view taken substantially along the line 4—4 of Fig. 3.

Fig. 5 is a vertical sectional view taken substantially along the section line 5—5 of Fig. 3.

Fig. 6 is a plan view of one of the concrete forms used in fabricating the concrete structure of my improved bridge pier; and

Fig. 7 is a side elevation of the form shown in Fig. 6.

As shown in these drawings, my improved bridge pier comprises a relatively slender, tapering, concrete structure 5 formed with relatively wide, flat sides 6 and 7 and relatively narrow, rounded sides 8 and 9 which slope inwardly from the bottom to the top of the structure. This concrete structure is erected on bed rock 10 and has embedded therein a metallic reinforcing and anchoring frame 11 consisting principally of two pairs of tubular members, the members of one

pair being indicated at 12 and the members of the other pair being indicated at 13. These tubular members are grounded on the bed rock 10 and are inclined so that the members 12 lie parallel with the sloping side 6 of the concrete structure while the members 13 lie parallel with the sloping side 7 of the concrete structure. Each of the tubular members 12 and 13 is anchored in place by a relatively short metal dowel 14 extending downwardly through the lower end

thereof into a dowel-receiving hole 15 previously drilled in the bed rock 10. The dowels 14 are grouted to the walls of the holes 15 and to the surrounding lower portions of the tubular members with which they are associated. The upper portions of the tubular members 12 are tied together and braced by upper and lower lattice type struts 17 which are fastened, by suitable connecting members 18, to similar upper and lower struts 17 connecting and bracing the tubular members 13. The tubular members of each pair are also

tied together by crossed tie-rods 18 equipped with turnbuckles 19. Each tubular member 12 is also joined to the opposing tubular member 13 by a series of vertically spaced struts 20 between which are arranged crossed tie-rods 21 equipped with turnbuckles 22.

When the pier described herein is in service the vertical loads are carried principally by the concrete structure 5. The main functions of the embedded metal structure, including the interconnected tubular members and the dowels 14, are (1) to reinforce and strengthen the concrete structure; (2) to firmly anchor the concrete structure to the foundation; and (3) to provide adequate resistance against overturning or sidewise movement of the concrete structure by the service loads and stresses imposed thereon. In this connection it will be noted that the concrete structure extends above the embedded metal structure and is otherwise designed to carry vertical loads.

The improved steel reinforced, concrete pier described herein is preferably fabricated in the following manner: The tubular metal members 12 and 13 are initially grounded on the foundation or bed rock 10 in the inclined or sloping position shown in Fig. 5 and the upper portions of these tubular members are then interconnected by the bracing means previously described. The tubular members are used as guides for drills which are passed downwardly therethrough to drill the dowel-receiving holes 15 in the bed rock 10. The dowels 14 are then passed downwardly through the tubular members and driven or inserted into the holes 15. These dowels are then firmly fixed in position by grouting them to the walls of the openings or holes 15 and to the lower portions of the tubular members 12 and 13. The completed metal frame structure is then embedded in the concrete structure 5 which is built in sections, beginning with the bottom section A resting on the bed rock 10 and ending with the top section G which extends a suitable distance above the water line H. In the completed structure all spaces within and between the tubular metal members are completely filled by the concrete structure 5.

The various sections A to G inclusive of the concrete structure 5 are successively fabricated with the aid of suitable tapered forms such as indicated at 26 in Figs. 6 and 7. The forms used in fabricating the different sections of the concrete structure are exact duplicates except that they are graduated in size to impart to the concrete structure the tapered configuration previously referred to. As here shown each tapered form 26 comprises upper and lower angle iron frame members 28 and 29 to which the wall member 30 of the form is suitably secured, said wall 30 being braced on the outside by suitable vertically extending bracing members 31 extending between the top and bottom frame members 28 and 29. The top frame member 28 is smaller than the bottom frame member 29 and the wall 30 is formed so that it has a predetermined inward taper toward its upper edge. The sides of the wall 30 are braced against relative inward displacement by transversely extending upper and lower bracing members 32. During the building of the concrete structure 5 these forms 26 may be successively lowered to their proper concrete receiving positions from a platform mounted on top of the tubular members or from a frame carried by two barges.

Any suitable means may be provided for guid-

ing the forms 26 as they are successively lowered to their proper positions during the fabrication of the concrete structure. In the present instance upper and lower guide rods 35 are shown extending transversely across the form 26 near each end thereof in intersecting relation with cooperating guide rods 36 extending diagonally between the end and side portions of the form. These guide rods 35 and 36 are designed to engage the tubular members 12 and 13 as shown in Fig. 6 and thus properly guide the form to its final lowered position.

Having thus described the principles of my invention and the preferred embodiment thereof, it will be understood that various modifications may be resorted to within the scope and spirit of the invention as defined by the appended claims. For example, the tubular members 12 and 13 may be arranged so that when shown in a sectional view, such as Fig. 3, they would slope inwardly in somewhat the same manner as shown in Fig. 5.

I claim:

1. A bridge pier or the like comprising a concrete structure erected on a firm foundation and designed to carry the vertical loads, interconnected, laterally spaced vertically extending hollow, tubular, metal reinforcing members grounded on said foundation and embedded in said structure, said members terminating below the top of said structure, and relatively short anchoring dowels extending downwardly through the lower ends of said members into preformed sockets provided in said foundation, said anchoring dowels being grouted in place within said members and said sockets and terminating a substantial distance below the upper ends of said members.

2. A bridge pier or the like as set forth in claim 1, in which the tubular members are inclined to slope inwardly toward the top of the concrete structure.

3. A bridge pier or the like comprising a poured-in-place concrete structure erected on a firm foundation and designed to carry the vertical loads and a pre-placed metallic skeleton frame embedded in and bonded to said structure during the pouring thereof and anchored to said foundation to resist overturning and sidewise movements of said structure, said frame comprising a plurality of interconnected laterally spaced, vertically extending, tubular metal members grounded on said foundation, and relatively short load-transmitting dowels anchoring the tubular members to said foundation, each of said dowels extending downwardly through the lower end of one of said members into a preformed socket provided in the foundation and being grouted in place within said member and said socket and terminating a substantial distance below the upper end of said member, the size and strength characteristics and anchorage of said metal members being such as to effectively anchor and brace the concrete structure against all overturning or sidewise-displacing moments to which the concrete structure is subjected under ordinary service conditions.

4. A bridge pier or the like comprising a concrete structure erected on a firm foundation and designed to carry the vertical loads and a metallic, skeleton, reinforcing frame embedded in said structure and anchored to said foundation to resist overturning and sidewise movements of said structure, said frame comprising vertically extending, hollow, tubular members grounded on said foundation and terminating short of the top of said structure, bracing means interconnecting

the upper portions of said members and relatively short anchoring dowels extending downwardly from the lower ends of said members into pre-formed holes drilled in said foundation, said dowels extending only a relatively short distance upwardly within said tubular members and being grouted in place within said members and said holes.

5. A bridge pier or the like comprising a concrete structure erected on a firm foundation and designed to carry the vertical loads and a pre-formed metallic reinforcing frame embedded in said structure and anchored to said foundation to resist overturning and sidewise movements of said structure, said frame including vertically extending, hollow, tubular members which are grounded on the foundation and are inclined so that they slope inwardly toward the top of the concrete structure, said members terminating short of the top of said structure, bracing and spacing means interconnecting the upper portions of said tubular members and means firmly anchoring the lower ends of said tubular members to said foundation, said means comprising relatively short dowels having their upper portions grouted in place within the lower ends of said tubular members and their lower portions

grouted in place within holes provided in said foundation, said dowels extending only a relatively short distance upwardly within said tubular members and terminating a substantial distance below the upper ends of said members.

6. A bridge pier or the like comprising a concrete structure erected on a firm foundation and designed to carry the vertical loads and a metallic reinforcing frame embedded in said structure, 10 and anchored to said foundation to resist overturning and sidewise movements of said structure, said means comprising a plurality of laterally spaced, vertically extending tubular members which are grounded on the foundation and 15 are inclined to slope inwardly toward the top of the concrete structure, bracing members interconnecting the upper portions of said tubular members and anchoring dowels extending downwardly through the lower ends of the tubular members into the foundation.

7. A bridge pier as set forth in claim 1 in which the tubular members are inclined to slope inwardly toward the top of the concrete structure and in which the concrete structure is tapered to 20 ward the top thereof.

CHAUNCEY M. GOODRICH.
